UNITED STATES PATENT OFFICE.

ALEXANDER B. SHARP, OF STEUBENVILLE, OHIO.

GAS-BURNER.

1,388,609.

Specification of Letters Patent. Patented Aug. 23, 1921.

Application filed October 27, 1920. Serial No. 420,037.

To all whom it may concern:

Be it known that I, ALEXANDER B. SHARP, citizen of the United States, residing at Steubenville, in the county of Jefferson and 5 State of Ohio, have invented certain new and useful Improvements in Gas-Burners, of which the following is a specification.

This invention relates to a gas burner which is so constructed that, under all conditions, a uniform pressure of gas is supplied 10 to all the burner tips, thus insuring an equal heat throughout the extent of the burner area.

The burner is also so arranged that each of 15 the burner spuds carries twin holes for the outlet of the air and gas, thus providing an arrangement which is exceedingly satisfactory for the production of a maximum amount of heat with a minimum consumption 20 and a minimum size of burner.

More specifically, the burner consists of a loop, one leg of which is provided with a series of alining burner spuds each carrying twin holes. One leg of the loop constitutes 25 the admission passage for the gas and air while the other leg of the loop and the bend constitute a mixing and distributing chamber whereby a uniform pressure of gas is, under all conditions, delivered to the 30 twin holes of each burner spud regardless of their respective positions on the leg constituting the mixing and delivery or distributing chamber.

In the drawings:

35 Figure 1 is a longitudinal section through the burner in a vertical plane,

Fig. 2 is a top plan view, fragmentary,

Fig. 3 is a transverse vertical section on the line 3—3 of Fig. 1.

40 In detail:

The burner, in the preferred form herein illustrated, is a single unit casting in the form of a loop having legs 1 and 2 which are connected at one end by the loop portion or 45 bend 3 and are supported in spaced relation at the other end by the web 4. These two legs while of uniform width, in a transverse plane, vary in cross sectional area in a vertical plane, the leg 1 increasing in vertical 50 width toward the bend 3 and constituting the admission leg of the burner, and the leg 2 decreasing in width in a vertical plane in a direction away from the bend 3, the bend

3 being larger in cross sectional area than either of the legs mentioned at their largest 55 point. The upper surface of the leg 2 is formed into a burner face 5 carrying a series of spuds 6 of the form shown in Fig. 2, and each having two or more holes 7 for the outlet of the mixture of the air and gas, the 60 air and gas being mixed at the entrance to the leg 1 by the use of a suitable mixing valve A which does not constitute a part of the present invention except so far as it is combined with the remainder of the burner. 65 At each end of the burner face is a lug 8 having a hole 9 which provides for fastening the burner in place in any suitable location such as a fire-place, stove, or the like.

In operation:

The air and gas enter at the admission end of the leg 1 and during their passage through the leg 1 and around the enlarged bend 3 and into the distributing chamber 2 become thoroughly commingled, the passage of the 75 mixed air and gas being regulated throughout its course to the twin holes of the burner spuds by reason of the variation in area of the legs 1 and 2 coupled with the enlarged area of the bend 3. In this manner, a uniform pressure is obtained at all of the burner outlets or holes with the result that maximum heat is obtained with a minimum consumption of gas and a small burner proportionate to the production of heat.

Having thus described the invention, what is claimed as new is:

A gas burner consisting of a single integral casting and including a lower leg having an inlet opening at one end, the cross 90 sectional area of the leg progressively increasing from said inlet end to the opposite end, a vertically disposed return bend leading upwardly from the end of the lower leg remote from the inlet end, an upper leg extending from the bend longitudinally over the lower leg and progressively decreasing in cross sectional area from the bend, a channeled burner face extending along the upper side of the upper leg and open through its 95 entire bottom to the said leg, and a series of burner spuds extending along the top of the burner face from end to end thereof and each having a plurality of outlet openings.

In testimony whereof I affix my signature. 105
ALEXANDER B. SHARP. [L. s.]
